UNITED STATES PATENT OFFICE.

ALFRED E. M. SHAFFER, OF LEHIGHTON, AND ALBIN A. NORRMAN, OF TAMAQUA, PENNSYLVANIA.

TRAVELING-GRAVE STOKER.

Application filed July 24, 1925. Serial No. 45,853.

This invention relates to improvements in traveling grate stokers together with a new method of feeding fuel to the same, and wherein fine sizes of anthracite fuel Numbers 3 and 4 buckwheat and smaller can be more advantageously consumed than with the present day device for this purpose, and without recourse to the method of preparation known as pulverizing. The fuel is almost instantaneously ignited as it enters the combustion chamber, and maintained in constant motion, thereby always being in contact with sufficient oxygen to afford complete combustion.

In carrying out the invention we also provide a novel fuel conveying device, which conveys the fuel onto a traveling grate, the fuel passing through a curtain of hot gases, whereby the finer particles burn in suspension, while the heavier particles are ignited before striking the grate.

An important object of the invention resides in arranging the grate at an angle of inclination, so that the air passing through the grate has a tendency to throw the particles of fuel upwardly and forwardly with a churning effect, and consequently burn them in suspension.

Another object of the invention resides in the provision of means for admitting air into the combustion chamber from various points above and below the fire bed, and an arrangement of valves for controlling the admittance of said air, so that a proper amount of air is provided to meet the requirements under any and all conditions, and to take care of the volatile matter and fuel suspension.

A still further object of the invention resides in a novel grate construction, including a plurality of elongated sections pivotally connected together in endless formation, each section being supplied with air from the bottom, and exhausting said air from the top into the fire bed, each section having its own individual air supply, so that each section receives the proper amount of air without loss or leakage to any other section.

Again, we contemplate the provision of spaced series of independent air supply chambers for the different grate sections, each of said sections having two air receiving openings, one at each end located at opposite sides of the longitudinal medial line

of the bottom of the section, thus insuring a continued supply of air to the grate.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a front elevation of the apparatus.

Figure 2 is a side elevation.

Figure 3 is an enlarged vertical sectional view through the combustion chamber and grate.

Figure 4 is a sectional view on line 4-4 of Figure 3.

Figure 5 is a sectional view on line 5-5 of Figure 3.

Figure 6 is a sectional view on line 6-6 of Figure 4.

Figure 7 is a sectional view on line 7-7 of Figure 4.

Figure 8 is a sectional view on line 8-8 of Figure 4.

Figure 9 is a sectional view on line 9-9 of Figure 1.

Figure 10 is a sectional view on line 10-10 of Figure 1.

Figure 11 is a sectional view on line 11-11 of Figure 1.

Figure 12 is a sectional view through the fuel feeding device.

The apparatus is in the nature of a furnace indicated generally at 10 and including a combustion chamber 11 in which is arranged an endless traveling grate, clearly illustrated in Figures 3 and 9. It will be noted that this grate projects through an opening in one side of the apparatus inasmuch as it is used as an instrumentality by means of which the ashes are eventually removed, and deposited into a suitable receptacle not shown. This grate is made up of a plurality of elongated sections of box-like formation in cross section and indicated at 12. These sections are arranged side by side 105 and provided with apertured lugs or ears 13 to accommodate pivoted rods 14 which connect the adjacent sections together. The en-

tire grate structure is adapted to move or travel around a pair of spaced drums 15, each of which is provided with a circumferential series of depressions 16, adapted 5 to receive the pivot rods 14 above referred to. The shaft 17 of one of these drums is provided with a gear 18 arranged to operate in a suitable casing 19, which gear meshes with a worm 20 carried by a shaft 21 adapted to be operated by a motor or any other suitable source. A very slow motion is imparted to this grate, the speed being regulated or controlled by any suitable speed reducing device, not shown. As clearly illustrated in Figure 4, each grate section 12 is of hollow formation and reenforced by a longitudinally disposed rib 22. Each of these sections is provided with an air receiving opening 23 at each end located on opposite sides of the longitudinal medial line of the bottom of the section, while the top of each section is formed with a plurality of slots 24 which may extend either transversely or longitudinally of the section, the walls 25 of each slot being preferably tapered as shown to minimize resistance to the flow of air therethrough. By virtue of this construction, air is admitted into each grate section, and subsequently exhausted through 30 the slots 24 beneath the fire bed. The manner in which the air is conveyed into the various sections of the grate will be herein-after described. The turbulent motion imparted to the fuel is largely due to the discharge of air from the inclined grate structure. It will be noted upon inspection of Figures 3 and 9 that the lower run of the grate moves over a suitable guide or track indicated at 25. Drums 15 which are supported by shafts 17 above referred to support angle irons 26 which in turn support a drum 27 arranged to serve or act as an air seal between the rear of the combustion chamber and the atmosphere. It also prevents ashes from dropping into the opening. It will be further observed upon inspection of Figure 5 that the shaft 17 is made in sections, the adjacent ends of which being associated with a suitable coupling 28, 45 affords ease in removal or installation.

The air for the grate sections as well as for the other points of distribution about the combustion chamber is supplied by a main air duct, which of course is adapted to 55 be associated with a suitable source of air supply. This air duct includes an intermediate portion 29 which extends across the front of the apparatus and spaced parallel side portions 30. These portions are preferably of the cross sectional contour shown 60 in Figure 4, and designed to support a portion of the adjacent walls of the furnace structure 10. Arranged in juxtaposition to each side portion 30 of the main air duct is 65 a series of chambers or compartments 31,

having independent communication with said duct, as there is a valve 32 provided for each chamber to control communication between the latter and said duct. These valves are clearly shown in Figure 7, each 70 being carried by a threaded stem 33 threaded to suitable bushings 34 associated with the main air duct 30, and each controlled by a hand wheel 35, so that any one or combination of valves may be opened or closed as 75 desired. As shown in Figure 4, the grate sections are adapted to move over these opposed series of chambers 31, and as each of two openings 23 located on opposed sides of the longitudinal medial line of the bottom 80 communicate with the openings of the chambers 31, directly opposite one another, air from the latter passes into the vertical grate section. Consequently the grate sections communicate continuously with one or both 85 of the opposed air chambers of the respective series, thereby insuring the grate or each section thereof of a continued supply of air while the grate is in operation. However, inasmuch as each grate section is individually supplied with air from the chambers 31, it is manifest that any number of these chambers can be cut off from communication with the main air duct, so as to utilize a selected number of grate sections, 90 while at the same time the proper amount of air can be conducted to each section of the grate without loss or leakage to any other section. The upper run of the grate moves over what we term a wear plate 36, there being one of these plates reposing on each series of chambers 31, each plate having a number of spaced openings 37 equivalent to the number of chambers 31, the openings 37 registering with the outlet openings of the 100 respective chambers. Not only can the supply of air from the main duct to the chambers 31 be completely cut off, but it may also be regulated by a proper adjustment of the valves 32. During banking periods over-heating of the grate sections can be prevented by allowing the air to blow through them to the atmosphere. In addition to supplying the grate sections with air in the manner described, the combustion chamber may 110 also be supplied with air from the main duct at a point immediately above the fire bed, for which purpose the adjacent walls 10 of the combustion chamber are provided with air inlet pipes 38, clearly shown in Figure 120 4, which pipes of course communicate with the adjacent sides of the main air duct. For the purpose of controlling this connection we provide a valve 39, these valves 39 being arranged to operate within the main air 125 duct, and supported by threaded stems of adjusting elements 40 which may be readily manipulated in any suitable manner, that is to say, either by hand wheel or a chain 41 trained over a suitable pulley 42. Again, 130

air from the main duct can be introduced into the combustion chamber through the instrumentality of branch pipes 43 and 44 respectively, the pipe 43 communicating with a horizontally disposed port 45 provided with a vertically disposed port 46, this pipe directing the air toward the traveling grate. Each of these branch pipes has associated therewith a sliding valve 47 which controls communication therebetween and the main air duct each valve being connected with an operating lever 48, through the instrumentality of which the port valve can be properly adjusted.

15 The fine fuel is delivered into a plurality of hoppers 49, as clearly shown in Figure 1, which hoppers include horizontally disposed portions 50 which open into the fire box an appreciable distance above the traveling grate. The fuel of course gravitates toward the lower end of each hopper, and is forced therefrom into the fire box by means of sliding plungers 51. There is one of these plungers for each hopper, each plunger being connected with an operating rod 52, which in turn is connected with a crank portion 53 of the crank shaft 54. As shown in Figure 1, this shaft 54 is journaled in suitable bearings 55, and is adapted to be 25 rotated in any suitable manner. The shaft, however, is preferably provided with a gear 56 which meshes with a worm gear 57 carried by a shaft 58 adapted to be operated by a motor or any other suitable means. It 30 is of course to be understood that the speed of this shaft 58 can be regulated, so that the sliding plungers 51 are operated to force into the fire box the proper amount of fuel consistent with the amount of air admitted 35 therein to promote complete combustion. It might here be stated that the speed with which the grate is operated has no bearing whatever upon the rate of combustion, the grate being utilized to remove the ashes 40 from the fire box. As the fuel is forced into the fire box in the manner above described it falls through a curtain of hot gases rising from the fire box, thereby burning the fine particles in suspension, while the larger 45 particles of fuel are ignited before striking the grate. The grate sections are thus supplied with ignited fuel at all times, and complete combustion takes place within the fuel bed zone. The admittance of air into 50 the fire box from the various points above enumerated can be regulated or controlled by the various valves, the air imparting a turbulent motion to the fuel. Certain of the air inlet openings are so placed with relation to the burning fuel that the proper 55 amount of air is admitted to take care of the volatile matter, and fuel in suspension can be admitted and combined so that once the proper temperature is reached, the maximum rate of combustion will not be de- 60

pendent upon the device itself, but rather upon the ability of the associated parts to withstand the additional strains to which they are subjected.

While it is believed that the advantages 70 of the invention will be readily apparent from the foregoing description, we desire to have it understood that we do not limit ourselves to what is herein shown and described, and that such changes may be re- 75 sorted to when desired as fall within the scope of what is claimed.

What we claim is:

1. In combination, an endless grate including a plurality of pivotally connected 80 hollow grate sections, each having an air inlet opening adjacent each end, with said openings arranged on opposite sides of the longitudinal medial line of the bottom of said section, and a plurality of air exhaust 85 openings in the top thereof, means for operating said grate, and means for alternately supplying said air inlet openings with air when each grate section reaches predetermined positions in the course of its travel. 90

2. In combination, an endless grate including a plurality of pivotally connected hollow grate sections, means for operating said grate, each section having air inlet openings adjacent the ends thereof and arranged 95 on opposite sides of the longitudinal medial line of the bottom thereof, and air exhaust openings in the top, spaced series of separate air chambers above which the upper run of the grate is arranged to travel, valve 100 controlled means for supplying said chambers with air, the chambers of each series being provided with aligned outlet openings, one inlet opening of each grate section communicating successively with the outlet openings of one series, and the other inlet opening communicating successively with the outlet openings of the other series as the grate is operated, the inlet openings of each section communicating alternately 105 with respect to each other, with said outlet openings.

3. In combination, an endless grate including a plurality of pivotally connected hollow grate sections, means for operating said grate, each section having air inlet openings and air exhaust openings in the top, said inlet openings being arranged adjacent the ends and on opposite sides of the longitudinal medial line of the bottom, 115 spaced series of air chambers above which the upper run of the grate is arranged to travel, valve controlled means for supplying said chambers with air, the chambers of each series being provided with aligned outlet openings, one inlet opening of each grate section communicating successively with the outlet openings of one series, and the other inlet opening communicating successively with the outlet openings of the other 120 125 130

series as the grate is operated, the inlet openings of each section communicating alternately with respect to each other, with said outlet openings.

- 4. In combination, an endless grate including a plurality of pivotally connected hollow grate sections, each section having air inlet openings located adjacent the ends thereof and at opposite sides of the longitudinal medial line of the bottom, and a plurality of exhaust openings in the top, spaced 10 series of separate air chambers above which the upper run of the grate is arranged to travel, valve controlled means supplying 15 said chambers with air, means for operating

said grate, the chambers of each series being provided with aligned outlet openings, one inlet opening of each grate section communicating successively with the outlet openings of one series, and the other inlet opening communicating successively with the outlet openings of the other series as the grate is operated, the inlet openings of each section communicating alternately with respect to each other, with said outlet openings. 20 25

In testimony whereof we affix our signatures.

ALFRED E. M. SHAFER.
ALBIN A. NORRMAN.
